CLAIM

We claim the ornamental design for an egg dyeing cup, as shown and described.

DESCRIPTION

FIG. 1 is a front elevation view of the egg dyeing cup showing our novel design;

FIG. 2 is a rear elevation view thereof;

FIG. 3 is a left elevation view thereof;

FIG. 4 is a right elevation view thereof;

FIG. 5 is a top plan view thereof; and

FIG. 6 is a bottom plan view thereof; and,

FIG. 7 is a perspective view thereof.

The broken lines showing in all figures are for illustrative purposes only and form no part of the claimed design.
